AIR CONDITIONING APPARATUS

Filed Aug. 3, 1945

UNITED STATES PATENT OFFICE

2,480,306

AIR CONDITIONING APPARATUS

Jose Sanchis, Newark, N. J.

Application August 3, 1945, Serial No. 608,671

3 Claims. (Cl. 62—134)

1

This invention relates to apparatus for conditioning or cooling air, and has for one of its objects the provision of such a device which is self-contained and is adaptable for use in the home or office.

Another object of the invention is the provision of a cooling system of the character referred to which comprises a cabinet housing a refrigerating compartment from which cold water is pumped and circulated through a pair of oppositely disposed grill or lattice like radiators, the said radiators being at opposite ends of an enclosed compartment in which a fan rotates to draw warm or hot air through one of the said radiators and expell same through the other of said radiators, thus subjecting the said air to a double cooling action.

A further object of the invention is to so tilt or incline the radiators that the incoming and outgoing air will pass therethrough at the most advantageous angle.

Another object is to produce a device of the character described in which the maximum simplicity of construction and operation is secured.

Other objects and advantages will appear as the nature of the improvements is better understood, the invention consisting substantially in the novel arrangement and co-relation of parts herein fully described, and illustrated in the accompanying drawing, and then finally pointed out and specifically defined and indicated in the appended claims.

The disclosure made the basis of exemplifying the present inventive concept suggests a practical embodiment thereof, but the invention is not to be restricted to the exact details of this disclosure, and the latter therefore, is to be understood from an illustrative rather than a restrictive standpoint.

In carrying out a preferred embodiment of the invention, it was found desirable to provide a cabinet to be positioned in any desired place in a room, the said cabinet being divided into several compartments, in the lowermost of which a motor driven liquefying unit is located, the refrigerator coil of the liquefying unit extending into a water cooling compartment directly above the refrigerator compartment. A third compartment is positioned above the water cooling compartment in which is housed a motor driven pump. A pipe from the pump leads into the water compartment and a second pipe leads upwardly from the pump and is in direct communication with one of the inclined radiators formed at one end of the uppermost or air conditioning

10 5

compartment. The said radiator is connected by a pipe line to a second radiator at the opposite end of the air conditioning compartment and a water return pipe leads downwardly from the said second radiator to the water compartment.

The type of radiators employed is preferably of the screen or lattice type, spaces between the pipes thereof sloping upwardly and outwardly so that no direct blast of cold air will strike anyone in the room where the device is located.

In the drawing the single figure is a perspective view, mostly diagrammatic, of a preferred embodiment of the invention with the front wall thereof broken away to show the interior. In the said figure the numeral 1 denotes a cabinet having a bottom wall or base 2 upon which is mounted an electric motor 3. A liquefying unit 4 of any suitable type for the purpose is operated by a belt and pulley drive 5 from the motor 3. The refrigeration coil 6 of the liquefying unit 4 extends upwardly through a floor 7 of a water containing compartment 8. A drain cock 9 may be provided near the bottom and at one end of the said water compartment 8. Water may be admitted to the compartment through an inlet 9a.

A plate 10 covers the compartment 8 and provides a floor for a third compartment 11 in which is suitably located a pump 12 having a suction pipe 13 extending downwardly for a suitable distance into the water compartment 8. The said pump is driven from a thermostatically controlled electric motor 14 electrically connected to a thermostat 15 secured to one wall of the cabinet and which may be set so that the motor operates at any desired external temperature. The drive means between the motor and pump may comprise any suitable means, such as for instance a belt and pulley drive 16. The motor and pump 20 compartment is closed at the top by a plate 17 which forms the floor or base for an air cooling or conditioning compartment 18.

Secured to the base plate 17 is a pair of uprights 19 terminating in bearings 20 in which is journaled a shaft 21 supporting a fan 22. The said shaft 21 and fan 22 are driven by means of a belt 23 encompassing a pulley 24 on the shaft 21 and a pulley 25 on the motor shaft 26. The top of the compartment 18 is closed by a plate or top wall 27.

A pair of radiators 28 and 29 are positioned at the left and right, respectively, of the compartment 18. The said radiators are preferably of the grid or lattice type and are placed in inclined position so that the spaces or openings 30

between pipes or tubes 32 and 33 of the respective radiators extend upwardly and outwardly of the compartment 18. A pipe 34 extends upwardly from the pump 12 and leads into the radiator 28 which is connected to radiator 29 by a pipe 35. A return pipe 36 leads from radiator 29 to the water tank or compartment 8.

In operation, when the motor 14 is running, the belt 23 will drive the fan 22 and air will be sucked into the compartment 18 through either radiator 28 or 29 depending upon the direction of rotation of the fan 22. In the present instance, air is shown by arrows A as entering the compartment through the openings 31 in the radiator 29 and leaving as indicated by arrows B through the openings 30 in radiator 28.

It will be seen that due to the direction of slope of the openings 30 and 31 in the radiators, no air is directly drawn from below and none is blown downwardly, thus avoiding all possibilities of drafts. It will further be seen that the air leaving the radiator is thoroughly cooled as it is first cooled on the entrance side by direct contact with the radiator pipes of the device, is further cooled in the chamber 18 and finally by contacting the pipes on the exit side.

From the foregoing, it will be seen that the device herein described and illustrated is highly efficient, will thoroughly cool the air and will cause no undue drafts but will provide a steady circulation of cool air wherever used.

It is apparent that the illustration shown above has been given by way of illustration and not by way of limitation and that the above structure is subject to wide variations and modifications, without departing from the scope or intent of the present invention. All of such variations and modifications are to be included within the scope of the present invention.

What is claimed is:

1. In an air conditioning and cooling device, a cabinet, a motor driven liquefying unit in the said cabinet, a water compartment, said liquefying unit comprising an evaporator coil extending into the water compartment, an air cooling compartment at the top of the cabinet, a pair of oppositely disposed interconnected radiators forming walls for said cooling compartment, said radiators comprising spaced apart pipes which slant upwardly and outwardly from the bottom of the air cooling compartment, a water circulating system connecting the water chamber to the radiators, and a fan for drawing air through the spaces between the pipes of one radiator and expelling same through the spaces of the opposite radiator.

2. An air conditioning and cooling device, comprising a cabinet, a lowermost compartment in

said cabinet, a water containing compartment above the lowermost compartment, a third compartment above the water containing compartment, an air cooling compartment above the last mentioned compartment, a motor driven liquefying unit in the lowermost compartment, said liquefying unit comprising an evaporator coil extending into the water compartment, a water circulating system comprising a pump in the third compartment, a motor operatively connected to said pump for driving same, a pipe extending from the pump into the water chamber, a pair of interconnected inclined radiators disposed at opposite sides of the air cooling compartment, said radiators comprising spaced apart pipes which slant upwardly and outwardly from the bottom of the air cooling compartment, a pipe connecting the pump to one of said radiators, a return pipe extending from the other of said radiators to the water compartment and a fan in the air cooling chamber driven by the pump motor for drawing air to be cooled through the spaces between the pipes of one radiator and expelling same through the spaces of the opposite radiator.

3. An air conditioning and cooling device, comprising a cabinet, a lowermost compartment in said cabinet, a water containing compartment above the lowermost compartment, a third compartment above the water containing compartment, an air cooling compartment above the last mentioned compartment, a motor driven liquefying unit in the lowermost compartment, said liquefying unit comprising an evaporator coil extending into the water compartment, a water circulating system comprising a pump in the third compartment, a motor operatively connected to said pump for driving same, a pair of interconnected inclined grid type radiators disposed at opposite sides of the air cooling compartment, pipes for connecting the pump to the water compartment and to the radiators, a return pipe from the radiators to the water compartment, and a fan in the air cooling chamber driven by the pump motor as and for the purpose specified.
